UNITED STATES PATENT OFFICE.

CYRUS L. SULZBERGER, OF NEW YORK, N. Y.

DESIGN FOR SKIRT-BINDING.

SPECIFICATION forming part of Design No. 29,858, dated December 20, 1898.

Application filed November 10, 1898. Serial No. 696,088. Term of patent 14 years.

To all whom it may concern:

Be it known that I, CYRUS L. SULZBERGER, of the city of New York, borough of Manhattan, in the county and State of New York, have invented and produced a new and original Design for a Skirt-Binding, of which the following is a full, clear, and exact description.

Reference is to be had to the accompanying drawings, forming a part of this specification, in which similar characters of reference indicate corresponding parts in all the views.

Figure 1 is a face view of a skirt-binding, showing my design. Fig. 2 is a rear face view of the same, and Fig. 3 is a transverse section of the same on the line 3 3 in Fig. 1.

The design in its entirety consists of a body A, with the lower portion doubled, as at A', the front or obverse of the body having a velvety effect and the back or reverse thereof appearing striped in a diagonal direction, ex-

cept the lower doubled-up part, which appears having a velvety effect, and from the lower edge of the body A depends a brush B, a row of stitches C appearing on both the front and the back of the binding over adjacent edges of the head B' of the brush and the doubled-up part A' of the body A.

The leading feature of the design consists of the body A, appearing doubled at the lower portion, a depending brush B, and stitching C appearing on both the front and back of the binding over the adjacent edges of the head of the brush and the doubled-up part of the body.

I claim—

The design for a skirt-binding, as herein shown and described.

CYRUS L. SULZBERGER.
